Attwad Kautz Attorney

UNITED STATES PATENT OFFICE.

BERNARD ZAIKOSKI, OF NEW YORK, N. Y.

STARTING MECHANISM FOR INTERNAL-COMBUSTION ENGINES.

Application filed April 17, 1922. Serial No. 553,681.

To all whom it may concern:

Be it known that I, BERNARD ZAIKOSKI, a citizen of Russia, who has taken out his first United States citizenship papers, residing at 5 New York city, in the county of Richmond and State of New York, have invented certain new and useful Improvements in Starting Mechanism for Internal-Combustion Engines, fully described and represented in 10 the following specification and the accompanying drawings, forming a part of the same.

This invention relates to starting mechanism for internal combustion engines and 15 aims to provide means for disconnecting the engine from the part of the mechanism to which the starting force is applied in case the engine starts to rotate backwards.

The invention is of particular value when 20 used in connection with a hand turned starting crank. Starting an internal combustion engine with such a crank has heretofore been dangerous for when the initial explosion in a cylinder of the engine turns the 25 engine backwards the back-kick on the starting crank has often resulted in breaking the arm of the person turning the crank. With the mechanism of the present invention all danger of back-kick on the starting 30 crank and the injury frequently resulting therefrom is eliminated.

Starting mechanism involving the invention includes a normally stationary member which is so connected to a member rotating 35 with the engine that a backward rotation of the engine causes a backward rotation of the normally stationary member. The initial backward turning of the normally stationary member is utilized to disconnect the engine from the starting crank before any material back-kick has been applied to the starting crank by the engine. A further feature of the invention consists in mechanism which utilizes a further backward 40 turning of the normally stationary member to disconnect this member from the engine.

In order that the invention may clearly be understood, I will describe in detail the embodiments of it which are illustrated in the accompanying drawings; in which—

Fig. 1 is a plan view of the preferred embodiment of the invention;

Fig. 2 is a transverse section on the line 55 2—2 of Fig. 1;

Fig. 3 is a transverse section on the line 3—3 of Fig. 1;

Fig. 4 is a horizontal section on the line 4—4 of Figs. 2 and 3;

Fig. 5 is an enlarged fragmentary trans- 60 verse section on the line 5—5 of Fig. 4; and

Fig. 6 is a view similar to Fig. 4 showing a modified form of the invention.

The starting mechanism illustrated in 65 Figs. 1 to 5 is mounted on a fixed frame having two side bars 10 and 11. The frame is mounted near the front end of the shaft 13 of the internal combustion engine in connection with which the device is to be used. The force-receiving member is a sleeve 15 70 journaled in a hole 16 in the bar 11. The starting force is applied to this sleeve by means of a hand operated crank 17 having fixed at its inner end a sleeve 18 whose internal cross-section is square and fits over a 75 squared portion 19 at the outer end of the sleeve 15.

The force-applying member by means of which the starting force is applied to the engine shaft 13 comprises a shaft 27 carrying a tooth clutch member 25 adapted to engage a similar clutch member upon the engine shaft 13. The shaft 27 is journaled 80 in the bar 10 and within the sleeve 15.

A driving connection is provided between 85 the force-receiving sleeve 15 and the force-applying shaft 27. This driving connection includes the elements next to be described:—A sprocket wheel 30 is mounted on the sleeve 15 and keyed thereto. A sprocket 90 chain 31 connects the sprocket wheel 30 with a sprocket wheel 32 mounted on a sleeve 33 which is fixedly mounted on a stub shaft 34 journalled in the bar 11 and in a sleeve 35 which is in turn journalled in the bar 10. 95 The sprocket wheel 32 is connected to the sleeve 33 by a key 32' which may be made integral with the sprocket wheel and which projects into a keyway 33' formed in the sleeve 33. The inner end of the sleeve 33 100 and the outer end of the sleeve 35 are shaped to form a toothed clutch 37 which is normally closed by a spring 38, and which serves to transmit forward rotation of the sleeve 33 to the sleeve 35. On the sleeve 33 105 is a cam 36 which serves to release the clutch

37 when it is moved outwardly so as to compress the spring 38. The sleeve 35 may be strengthened by a short stub shaft 38 fixed therein. On the sleeve 35, and preferably 5 made integral therewith as shown, is a pinion 39 which meshes with a gear 40 rotatably mounted on a shaft 41 fixed in the bars 10 and 11. The gear 40 meshes with a pinion 42 keyed on the force-applying shaft 27. It is apparent that the connecting 10 mechanism which has been described provides means for turning the shaft 27 in a clockwise direction and cranking the engine through the clutches 25, 26 when a force is applied to the crank 17 to turn the sleeve 15 in a clockwise direction looking from the front. Rotation of the shaft 27 and the crank 17 in this direction is hereinafter referred to as "forward" rotation of these 15 parts. The rotation of the other elements of the connecting mechanism which takes place on a forward rotation of the sleeve 15 and the shaft 27 is referred to as forward rotation of these elements. Thus, it is apparent that forward rotation of the gear wheel 40 is rotation in an anti-clockwise direction looking from the front.

An important feature of the connecting mechanism lies in the fact that the force 30 receiving sleeve 15 and the force applying shaft 17 are coaxial with each other. This makes it possible to provide a spring for normally holding the clutch member 25 out of engagement with the clutch member 26 35 and to cause the engagement of these clutch members by pushing in axially on the crank 17. For this purpose a pin or screw 43 is secured in the outer end of the shaft 27. This pin has a running fit in an axial hole 44 in the crank 17 and a shoulder 45 engaging the outer side of the crank. A compression spring 46 is provided within the sleeve 18. This spring reacts between the outer end of the sleeve 15 and the inner side of the crank 17, and normally thrusts the crank 17 outwardly drawing the shaft 27 outwardly and disengaging the clutch member 25 from the clutch member 26. When force is to be applied to the crank 17 to 40 crank the engine, the crank is also pushed in axially against the force of the spring 46. This pushes the shaft 27 inward and brings the clutch member 25 into engagement with the clutch member 26, so that the rotation of the shaft 27 is transferred to the engine shaft 13.

The provision of the sprocket wheels 30, 32 and the chain 31 in the connecting mechanism facilitates varying the gear ratio and thus varying the relative rate of rotation of the force receiving sleeve 15 and the force applying shaft 27. This may be done by merely substituting for the sprockets 30 and 32 similar sprockets of different relative diameter. I find it most desirable, however,

to make the sprocket 30 larger than the sprocket 32, as illustrated, so that the shaft 27 is rotated more rapidly than the sleeve 15. This facilitates spinning the engine and thus insures starting it. It, of course, requires the application of a greater turning force to the crank 17 than would be necessary if the sleeve 15 and the shaft 27 were connected so as to rotate at the same speed. I have found, however, that the operator 70 may easily apply a greater force to the crank 17 in the use of the new starting mechanism than it has been heretofore customary to apply to starting cranks, because by means of the mechanism next to be described, the operator is insured against the danger of a back-kick on the crank in case the engine starts to turn backward.

Clutch releasing mechanism is provided for releasing the clutch 37 in case the shaft 27 is turned backward by a backward turning of the engine shaft. This mechanism includes a member connected to rotate with the force applying member and consequently with the engine shaft and a normally stationary clutch actuating member coaxial with the rotary member. In the form illustrated the rotary member of the releasing mechanism is the gear wheel 14 which, in this instance also forms a part of the connecting mechanism between the force-receiving member and the force-applying member as already explained. The normally stationary clutch actuating member 50 includes a hub 51 turnably mounted on the shaft 41, a wheel 52 and most desirably made integral therewith as shown, and a cam member 53 secured to the hub 51 by means of a set screw 54. The normally stationary member 50 is retained against forward rotation, that is, as hereinbefore explained, rotation in anti-clockwise direction looking from the front, by a radial stop bar 55 projecting from the wheel 52 and engaging the lower side of the sleeve 35. The member 50 is normally held against backward rotation by a spring 56 which has one of its ends 57 secured in a hole 58 in the fixed shaft 41 and its other end 59 secured to the stop bar 55. The spring 56 is wound around the fixed 100 shaft 41 in such manner that its end 59 tends to cause a forward rotation of the normally stationary member 50, thus retaining the stop bar 55 in contact with the sleeve 35.

Connecting means are provided between the rotary member 40 and a normally stationary member 50 which serve to lock these members together in case of backward rotation of the rotary member 40 under the influence of a backward turning of the engine shaft 13. These means include a ratchet ring 65 secured to the rotary member 40 by screws 66, and a plurality of pawls 67 pivotally mounted upon screws 68 ex- 120 130

tending between the spokes 69 of the wheel 52. Springs 70 secured to the wheel 52 normally thrust the pawls 67 forward against the teeth of the ratchet ring 65. The teeth 5 of the ratchet ring 65 and the surfaces of the pawls 67 are inclined in such manner that the teeth pass over the pawls without engagement therewith when the rotary member 40 is turned forward. But when 10 the rotary member 40 is turned backward the teeth of the ring 65 engage the pawls 67 and lock the rotary member 40 to the normally stationary member 50. In order to insure an immediate locking together of 15 the members, as soon as the rotary member 40 starts to turn backward the pawls 67 are positioned about the wheel 52 in such a manner that they lie opposite different portions of the teeth of the ratchet ring 65 20 (see Fig. 2). Consequently, a backward turning of the rotary member 40 through a distance of not more than one-quarter of the width of a tooth of the ring 65 is always sufficient to lock one of the teeth with one 25 of the pawls.

The cam member 53 includes an arc-shaped bar 75 spaced outwardly from the hub 51 and providing a substantially radial surface 76 terminating in an inclined surface 77 which is located closely adjacent to the cam 36 on the sleeve 33 when the normally stationary member 50 is in its normal position with its stop bar 55 in engagement with the sleeve 35. Upon a backward turning 30 of the normally stationary member the surface 77 immediately engages the cam 36 thrusting the cam and the sleeve 33 on which it is mounted outwardly against the force of the spring 38 and releasing the clutch 37. It should be noted that the release of the clutch is effected by angular movement, as distinguished from axial movement, of the normally stationary member 50, so that the release is practically instantaneous upon the initial backward turning 45 of the normally stationary member.

Means are provided for disconnecting the normally stationary member 50 from the rotary member 40 in case of a continued backward turning of the rotary member 40 after the normally stationary member has been turned backward sufficiently to cause the cam member 53 to release the clutch 37. These means include stops 80 extending between 50 the spokes 69 of the wheel 51 and limiting the forward movement of the pawls 67, and include also a left hand worm 81 formed on the fixed shaft 41 and a nut 82 engaging the threads of the worm 81 and secured to the hub 51 by the set screw 54. Since the normally stationary member 50 is mounted in this manner upon the worm 81 a continued backward turning of the normally stationary member moves it axially 55 away from the rotary member 40, bringing

the pawls 67, which are retained against the stops 80, out of engagement with the teeth of the ratchet ring 65. The surface 76 of the bar 75 of the cam member 53 is spirally curved so as to permit this axial 60 movement of the normally stationary member 49 while the surface 76 remains in engagement with the cam 36.

The use and operation of the device described will be apparent to those skilled in the art from the foregoing description.

The modification illustrated in Fig. 6 is similar to the form already described, except that pinions 130 and 132 are substituted for the sprocket wheels 30 and 32 and 65 these pinions are connected by a gear wheel 131 rotatably mounted upon the fixed shaft 41, instead of by a sprocket chain. In the arrangement illustrated in Fig. 6, the pinions 130 and 131 are both the same size so 70 that the shaft 27 rotates at the same speed as the sleeve 15.

I wish it clearly understood that my invention is by no means limited to the specific embodiments which have been illustrated 75 and described, as it will be apparent to those skilled in the art that many changes both in the form and in the location of the various elements of the mechanism may be made without departing from the principles of 80 the invention.

What is claimed is:

1. A starter for internal combustion engines, comprising a force receiving member, a force applying member, a connection between said members including a normally closed clutch, a rotatable member connected with the force applying member, a normally stationary clutch actuating member coaxial with said rotary member and arranged to release said clutch by a backward angular movement, and means adapted to connect said rotatable member with said normally stationary member when said rotary member is turned backwards.

2. A starter for internal combustion engines, comprising a force receiving member, a force applying member, a connection between said members including a normally closed clutch, a rotatable member connected with the force applying member, a normally stationary clutch actuating member coaxial with said rotary member and arranged to release said clutch by a backward angular movement, and a pawl and ratchet connection between said rotary member and said normally stationary member adapted to transfer backward rotation of said rotary member to said normally stationary member.

3. A starter for internal combustion engines, comprising a force receiving member, a force applying member, a connection between said members including a normally closed clutch having a slid able member, a

rotatable member connected with the force receiving member, a normally stationary clutch actuating member coaxial with said force receiving member and having a part 5 spaced outwardly from its axis and positioned to engage the slidable member of said clutch and release said clutch by a backward angular movement, and means for connecting said rotary member with 10 said normally stationary member on backward rotation of said rotary member.

4. A starter for internal combustion engines, comprising a force receiving member, a force applying member, a connection between 15 said members including a normally closed clutch having a slidable member, a cam connected to the slidable member of said clutch, a rotatable member connected with the force receiving member, a normally stationary clutch actuating member coaxial with said rotary member and including a cam spaced outwardly from its axis and adapted to engage the clutch cam and release the clutch on a backward angular 20 movement of said normally stationary member, and means for connecting said rotary member with said normally stationary member on a backward rotation of said normally stationary member.

5. A starter for internal combustion engines, comprising a force receiving member, a force applying member, a connection between 25 said members including a normally closed clutch having an axially slid able element, a cam on said axially slid able member, a rotatable member connected with the force receiving member and having its axis parallel to the axis of said clutch, a normally stationary clutch actuating member 30 coaxial with said rotary member and including a cam having an inclined surface adapted to engage said clutch cam and release the clutch on an initial backward angular movement of said normally stationary member and having a substantially radial surface adapted to remain in engagement 35 with said clutch cam and retain said clutch in open position on a further backward angular movement of said normally stationary member, and means for connecting said rotary member and said normally stationary member on a backward turning of said rotary member.

6. A starter for internal combustion engines, comprising a force receiving member, a force applying member, a connection between 40 said members including a normally closed clutch, a rotatable member connected with said force applying member, a normally stationary clutch actuating member coaxial with said rotary member and arranged to release said clutch by a small 45 backward angular movement, means for connecting said rotatable member to said normally stationary member on an initial

backward turning of said rotary member, and means for disconnecting said normally stationary member from said rotary member upon a further backward turning of said rotary member. 70

7. A starter for internal combustion engines, comprising a force receiving member, a force applying member, a connection between 75 said members including a normally closed clutch, a rotatable member connected with the force applying member, a normally stationary clutch actuating member coaxial with said rotary member and arranged to release said clutch by a backward angular movement, means for positively holding 80 said normally stationary member against forward rotation, yieldable means normally restraining said normally stationary member against backward rotation, and means adapted to connect said rotatable member with said normally stationary member when said rotary member is turned backwards.

8. A starter for internal combustion engines, comprising a force receiving member, 90 a force applying member, a connection between said members including a normally closed clutch, a rotatable member connected with the force applying member, a normally stationary clutch actuating member coaxial 95 with said rotary member and arranged to release said clutch by a backward angular movement, a fixed stop, a radial stop bar on said normally stationary member adapted to engage said stop to prevent forward turning 100 of said normally stationary member, a spring arranged to urge said stop bar against said stop and to resist backward turning of said normally stationary member, and a pawl and ratchet connection between said rotary member and said normally stationary member adapted to transfer backward rotation of 105 said rotary member to said normally stationary member.

9. A starter for internal combustion engines, comprising a rotatable force receiving member, a rotary force applying member, a train of connecting mechanism between 110 said members adapted to cause said force applying member to rotate more rapidly than said force receiving member and including a normally closed clutch, a rotatable member connected with the force applying member, a normally stationary clutch actuating member coaxial with said rotary member and arranged to release said clutch by a backward angular movement, and means adapted to connect said rotatable member with said normally stationary member when 115 said rotary member is turned backwards. 125

10. A starter for internal combustion engines, comprising a rotatable force receiving member, a rotary force applying member, a train of connecting mechanism between 130 said members including a pair of

sprockets, a chain connecting said sprockets and a normally closed clutch, a rotatable member connected with the force applying member, a normally stationary clutch actuating member coaxial with said rotary member and arranged to release said clutch by a backward angular movement, and means adapted to connect said rotatable member with said normally stationary member when said rotary member is turned backwards.

5 tuating member coaxial with said rotary member and arranged to release said clutch by a backward angular movement, and means adapted to connect said rotatable member with said normally stationary member when

10 said rotary member is turned backwards.

11. A starter for internal combustion engines, comprising a force receiving member, a force applying member, a connection between said members including a normally closed clutch and a rotatable member, a nor-

mally stationary clutch actuating member coaxial with said rotary member and arranged to release said clutch by a backward angular movement, and means adapted to connect said rotatable member with said normally stationary member when said rotary member is turned backwards.

20 In testimony whereof I have hereunto set my hand in the presence of two subscribing witnesses.
